UNITED STATES PATENT OFFICE

WILLIS H. COLBY, OF MOREHEAD CITY, NORTH CAROLINA

CHILD'S BUILDING BLOCK

Application filed November 22, 1929. Serial No. 409,097.

This invention aims to provide novel means for interlocking and connecting blocks of the kind used by children in building toy houses, and other structures.

5 It is within the province of the disclosure to improve generally and to enhance the utility of devices of that type to which the present invention appertains.

With the above and other objects in view, 10 which will appear as the description proceeds, the invention resides in the combination and arrangement of parts and in the details of construction hereinafter described and claimed, it being understood that changes 15 may be made in the precise embodiment of the invention herein disclosed, within the scope of what is claimed, without departing from the spirit of the invention.

In the accompanying drawings:

20 Figure 1 shows in perspective, a piece of wall constructed in accordance with the invention, parts being broken away;

Figure 2 is a vertical section of a partly erected wall, parts being in elevation;

25 Figure 3 is a perspective view showing one of the blocks;

Figure 4 is a perspective view of the key;

Figure 5 is a perspective disclosing a modified block.

30 The block shown in Figure 3 is marked by the numeral 1 and has rectangular slots in its ends. The slots are marked by the numeral 2. Pins 3 project from one side of the block 1, and the opposite side of the block is provided 35 with holes 4 adapted to receive one or both of the pins of a similar block, the holes 4 being counter-sunk, as at 5, and the pins 3 being pointed, as shown at 6, if preferred, to facilitate the insertion of the pins 3 of one block 40 into the holes 4 of one or more adjoining blocks, when the blocks are laid in superposed courses, as indicated in Figure 1.

When the blocks are arranged as before described, the slots 2 in the ends of adjoining blocks are in registration, and rectangular keys 7 may be slid into the registering slots, the keys 7 fitting closely but slidably in the registering slots.

45 At the corners of the structure, corner blocks 8 are provided. One end face 9 of the

corner block has no slot in it, but is plain. The block 8 has a slot 28 in one side, and this slot cooperates with one of the slots 2 of an adjoining block to receive the key 7.

The block may be made in various ways 55 and of various sizes.

In Figure 5 of the drawings, there is disclosed a rectangular block provided at one end 11 with a rectangular slot 12, and provided at the opposite end 10 with a rectangular slot 14, the slots being of the same size and shape. The block is provided on one side 15 with projecting pins 16 which may be pointed, as shown at 17. The block is provided on its opposite side 18 with an opening 19 which is counter-sunk, as shown at 20, the opening 19 being so shaped as to receive the pin of a similar block. The side 18 of the block has a transverse slot 21 disposed at right angles to the slots 12 and 14 60 in the respective ends 11 and 10 of the block. The transverse slot 21 is spaced from one end 11 by a distance 22 equal to the distance 23 between either of the slots 12—14 in the ends of the block and the remaining side 24 of 65 the block.

The transverse slot 21 is spaced from one end 11 by a distance 22 equal to the distance 23 between either of the slots 12—14 in the ends of the block and the remaining side 24 of 70 the block.

75 As a consequence, when the removable key is slid into the registering slots 21 and 12, the block shown in Figure 5 will not project at its end beyond the side of the block to 80 which it is coupled by the key 7. Several of the blocks shown in Figure 5, therefore, may be placed vertically, to form, for instance, the post of a door or window, and to the uppermost of the said blocks may be coupled 85 one of a plurality of like horizontally disposed blocks, which form the lintel.

Various materials of construction can be used without departing from the spirit of the invention. If desired, the blocks may be 90 made of wood, and the pins may be made of metal, although this selection of materials is not insisted upon.

What is claimed is:

A rectangular block of the class described, 95 provided in its ends with like slots, the block being supplied on one side with projecting pins spaced apart longitudinally of the block, the block being provided on its opposite side with an opening so shaped as to receive the 100

pin of a similar block, the last-specified side of the block having a transverse slot disposed at right angles to the slots in the ends of the blocks of the same size and shape as the slots in the ends of the block, the transverse slot being spaced from one end of the block by a distance equal to the distance between either of the slots in the ends of the block and the remaining side of the block.

In testimony that I claim the foregoing as my own, I have hereto affixed my signature.

WILLIS H. COLBY.
